US00D560740S

(12) **United States Design Patent** (10) **Patent No.:** **US D560,740 S**
(45) **Date of Patent:** ** *Jan. 29, 2008

(54) **PLAYGROUND EQUIPMENT**

(75) Inventors: **Bryan Phelps**, Roy, UT (US); **Corey Phillips**, Roy, UT (US)

(73) Assignee: **Performance Design, Inc.**, Clearfield, UT (US)

(*) Notice: This patent is subject to a terminal disclaimer.

(**) Term: **14 Years**

(21) Appl. No.: **29/265,013**

(22) Filed: **Aug. 23, 2006**

(51) **LOC (8) Cl.** **08-07**

(52) **U.S. Cl.** **D21/826**

(58) **Field of Classification Search** D21/811, D21/814, 818-827; 482/35, 36; 472/116-117
See application file for complete search history.
